CLAIM

The ornamental design for a combined trash and recycling receptacle, as shown and described.

DESCRIPTION

FIG. 1 is a perspective view of a receptacle having a first bottom section of the present invention;
FIG. 2 is a first side view of the receptacle of FIG. 1;
FIG. 3 is a second side view of the receptacle of FIG. 1;
FIG. 4 is a third side view of the receptacle of FIG. 1;
FIG. 5 is a fourth side view of the receptacle of FIG. 1;
FIG. 6 is top view of the receptacle of FIG. 1;
FIG. 7 is a bottom view of the receptacle of FIG. 1;
FIG. 8 is a perspective view of the receptacle having a second bottom section of the present invention;
FIG. 9 is a first side view of the receptacle of FIG. 8;
FIG. 10 is a second side view of the receptacle of FIG. 8;
FIG. 11 is a third side view of the receptacle of FIG. 8;
FIG. 12 is a fourth side view of the receptacle of FIG. 8;
FIG. 13 is top view of the receptacle of FIG. 8; and,
FIG. 14 is a bottom view of the receptacle of FIG. 8.
The broken lines showing additional features of the receptacle are for illustrative purposes only and form no part of the claimed design.
